UNITED STATES PATENT OFFICE

2,488,207

RADIO PROGRAM SELECTOR

Walter Alexander Lea, Los Angeles, Calif., assignor of one-third to George Henry Cunningham and one-third to Nils A. Thiebaud, both of Los Angeles, Calif.

Application February 23, 1945, Serial No. 579,470

7 Claims. (Cl. 250—20)

1

The invention relates to a program selector and more particularly to tape controlled apparatus employing a tape having punch marks which form a record of desired radio programs, the tape controlling the apparatus to turn a radio receiver on or off and change or select a broadcast station.

Paper may be used as the tape. If the tape is employed to break a control circuit, an electric spark results which may damage or burn the tape. This is overcome according to the present invention by employing the tape only to make the control circuit, not to break it, the circuit being broken elsewhere remote from the tape. For this purpose, the invention provides a switch which may be designated a selector switch for each tuning device and for the power supply circuit, with means operative, when the tape operates a particular switch, to (1) lock that switch in actuated position, (2) open the energizing circuit of that switch, and (3) restore the previously actuated switch to the control of the tape, thus saving current.

Use may be made of an endless tape or a strip of tape having ends. When using a strip of tape, it has been found that when the end of the tape arrives in the apparatus, a noise is produced in the radio receiver due to the fact that all the selector switches are energized whereby the tuning devices and power supply circuit are incessantly and rapidly cut in and out of circuit, as a switch when energized releases the others, and when a switch is released it is immediately energized again. This defect is overcome according to the present invention by rendering ineffective the tape control of the selector switches when the end of the tape arrives. Also before the end of the tape arrives, assuming the program is over, a punch mark in the tape is operative to operate the power supply selector switch which mechanically locks up, using no current, with the power supply cut off and with the tuning control selector switches in idle position. When the same or another tape is started through the apparatus, it is not necessary to start a program by using a punch mark for the power supply, as a punch mark for a given radio station operates the corresponding tuning control selector switch to thereby release the power supply selector switch to idle position and connect the power supply in circuit.

For further details of the invention, reference may be made to the drawings wherein—

Fig. 1 is a plan view, partly in section, looking down at the top of what is shown in Fig. 2.

Fig. 2 is a sectional elevation looking at the timing means as connected to actuate the tape record as the same is passed under electrical contacting fingers which are associated with the record tape.

2

Fig. 3 is an elevational view of a detail spring means for holding electrical contact fingers in place.

Fig. 4 is a plan view, with parts broken away, looking at the bottom of the spring means of Fig. 3.

Fig. 5 is an end view in elevation, with parts broken away, looking towards the right at the contact fingers in Fig. 3.

Fig. 6 is a plan detail on line 6—6 of Fig. 2, showing the mechanism for holding the tape in contact with the feed drum which is actuated by the timing means.

Fig. 7 is a plan view of a set of stripping fingers 15 contacting the inside of the record tape for stripping the tape from the feed drum. These fingers are indicated in Fig. 2.

Fig. 8 is a vertical elevation of a magnetic switching block, parts of which are omitted for 20 clearness of illustration.

Fig. 9 is a sectional elevation of one of the magnetic switching blocks of which there are a plural number shown in Fig. 8. What is shown in Fig. 9 is a transverse view as to what is shown at 25 the left unit as shown in Fig. 8. This being a single unit of a magnetic switch connected into the system for any given single radio circuit, there being a plurality of this structure as indicated by Fig. 9 in any given unit of my invention. These 30 units of Fig. 9 switch in and out any radio program arranged for by the holes in the record tape.

Fig. 10 is a transverse detail looking in the opposite direction on line 10—10 of Fig. 8.

Fig. 11 is a vertical elevation on line 11—11 of 35 Fig. 8 of a magnetic switch unit, of which only one unit is used in the magnetic switching block and this unit is indicated by the unit at the right end of Fig. 8. The purpose of this switching unit of Fig. 11 is to switch on and off the line current of any electrical supply needed in the use of my invention.

Fig. 12 is a wiring diagram indicating the 40 electrical circuits which are switched in and out by the magnetic construction of what are indicated in Figs. 8, 9 and 11.

Fig. 13 is a sectional view similar in part to Fig. 11 showing some of the parts in different position from what is shown in Fig. 11.

Fig. 14 is a plan view on line 14—14 of Fig. 8.

Fig. 15 is a vertical sectional elevation through a part of a solenoid as shown in Fig. 9.

Fig. 16 is a perspective view of a wiring 50 connection to a solenoid.

Fig. 17 is a perspective view of a switching block as relates to the electrical contact the details of which will be described later.

Fig. 18 is a perspective view of an interlocking 60 bar which holds a switch in a definite position.

With my invention, referring now to the drawing, tape 2 is made of any suitable material, such as paper. This strip of tape 2 is provided in the form of a definite length and width measured for the service desired and may be made as wide or as narrow as needed, and also as long as needed, to provide a sufficient area to carry seven lines of punch holes through the tape 2.

The tape here shown as to the number of lines of punch holes in the tape 2 is marked to carry five lines of punch holes for five different radio stations, each line representing one station. In addition to those five station lines there is another line of punched holes in the tape 2 and this line of holes control an operating switch which shuts off the electric current supply to the radio in which my magnetic switch is installed for any given unit of radio receiving set.

In addition to the above mentioned rows of holes in the said tape 2, there is another line of holes of a continuous line equidistantly spaced by the means of which the tape is fed continuously through the timing unit as herein described.

This tape is provided in a definite length to cover the number of radio programs to be provided for as desired. The tape may be made as continuous band or belt, or may be made in a definite length and have the ends joined together as desired or may be made in certain special cases as a continuous length sufficient to run for a given length of time, and then become discharged from the timing mechanisms and then re-entered as desired for further service.

Referring now to the clock or timing means as hereinbefore mentioned, the tape after being punched in any suitable manner with holes S, T, may be placed into the timing mechanisms as a single piece of tape of any given length or for a single or for a number of programs on one piece of tape. Or a given length of tape measured for a certain period of time may be made and punched for programs as desired and the ends of that tape connected together bringing about an endless ring of tape which is placed into the timing means to be passed through the said timing means completely around and around as many times as desired for any given service of programs.

The timing means in which the tape is used after having been prepared by the punching means are indicated by Figures 1 through 7. In this timing means the endless band of tape as mounted therein is indicated by 2. The timing means is indicated by a clock dial 61 in which the minute hand is indicated by 62 and the hour hand by 63. On the shaft of the hour hand there is a gear 64 see Figure 2. This gear 64 meshes into a connecting gear 65 which in turn meshes into a gear 66 on a shaft 67. A tape drum 68 is frictionally mounted on the shaft 67.

The tape drum 68 is provided at its middle portion with a sprocket wheel 69 which sprocket wheel engages the perforations 8 of the tape 2 as and when the tape 2 is mounted and trained around suitable guideways and idler supporting drum as desired in any given case.

The rows of holes in the tape 2 indicated by S and T being program system of holes, are synchronized to the time periods by means of revolving the drum 68 on the shaft 67 by frictional slippages on the shaft 67 without thereby revolving the shaft of the hand gear of the timing mechanisms. This frictional resistance is

carefully adjusted to revolve the tape drum but not the hour hand.

Mounted in a suitable frame and means for supporting the timing means, there is supported a table 70 over which the tape 2 is trained. This table 70 carries on its underside an insulating block 71 which extends to the left and is provided at the edge with contact bars 71a, 71b, the tops of which are flush with the table 70. 10 And to this contact bar 71a there is connected an electric conductor wire 72 connected to a spring switch blade 72a which is connected by conductor 72b to the secondary winding of the power supply transformer 73, see Fig. 2. As 15 shown in Fig. 4, the switch blade 72a is shunted by a conductor 172b connected at one end to conductor 72b and at its other end to the contact bar 71b.

Mounted in any suitable manner across the 20 top of the timing means as herein shown there is a rocking shaft 75 on which is fixed a block of insulating material 76. Connected into this block 76 there are a series of conductor fingers 77, the left ends of which are turned downward 25 and adapted to spring into the holes S and T in the tape 2 and thereby contact the bar 71a as the tape 2 is moved toward the left in Figures 1 and 2.

At the connection of the conductor fingers 77 30 with the block 76 there are screws 78 which clamp the fingers 77 to the block 76. Connected to the screws 78 there are conductor wires 79 which are combined in the cable 80 which extend to a switching block previously mentioned 35 in the early part of this specification.

In the use of this program selector, as a general situation, the record tape will be made in a continuous band, but it may be composed of special strips not connected together as a continuous band. These strips of any desired length will be inserted into the timing mechanisms manually by inserting the end of the strip into the feeding means provided in the timing means. The tape, when in the machine, as and 45 when it may be passed through to the end of any one strip, there would then occur a sudden contact of all the conductor fingers 77, making an electric disturbance of the program selector. To guard against such an emergency, I provide a 50 spring switch blade 72a as previously described, which becomes a circuit breaker. This is made of conducting material and is provided with an upward projecting portion 72d, which bears on the underside of the tape 2, see Figures 3, 4 and 55 5. Immediately above this projection 72d there is mounted a couple of small rollers 72c mounted on a spring arm 72f, which spring arm is secured to the underside of the block 76.

As and when the tape 2 passes along to where 60 the end of it clears the roller 72c, the spring 72f presses down the switch blade 72a, and thereby breaks open the electrical circuits to the timing mechanism, which circuits extend to the solenoid switching mechanisms as a safety device in using 65 the program selector. However be it observed that there is a shunt wire 172b that bridges around the opening caused by the roller 72c depressing switch lever 72a, which leaves closed the circuit from the segment of contact bar 71b to 70 the solenoid 106; thus when the tape runs out, the finger in position over segment 71b makes contact therewith, thus energizing solenoid 106 which acts to discontinue the electric service to the radio in which this unit is installed.

Any suitable means may be used for revolving

the shaft 75 in position to hold the contact fingers 77 in a slight spring pressure sufficient to cause any single finger 77 to drop through a hole in the tape and contact the electric conductor block 71a. As an example, see Fig. 3, wherein a vertical spring 81 is suitably mounted to the framework of the device to exert a pressure to the left and rock a radial arm 82 fixed on the shaft 75 whereby the spring 81 thereby holds the spring fingers 77 in contact with the tape 2.

At the left end of Figure 2 there is mounted a roller 83 to exert a slight pressure on the tape 2 for holding the tape in contact with the sprocket wheel 69 and on the drum 68. This roller 83 is in two sections straddling the sprocket wheel 69 and the roller is held in place by a spring arm 84 the ends of which are fixed to a block 85 on a shaft 86. The shaft 86 is mounted in any suitable manner in the framework of the device. On the end of the shaft 86 there is mounted a radial arm 87 which is hinged to a rod 88 which extends to the right and is hinged to the radial arm 82. Thus as the shaft 75 is moved by the vertical spring 81, that same movement acts upon the rod 88 to rock the shaft 86, and thereby hold the roller 83 to hold the tape 2 onto the drum 68. A handle 89 is provided for rocking the shaft 86 when the handle is lifted upwardly in a manner to lift the roller 83 clear of the tape 2 and the drum 68. When this action takes place the connecting rod 88 acts to rock the shaft 75 in the same direction as the shaft 86 is rocked. And this results in lifting the spring contact fingers 77, thus making a clear way to introduce a new tape or remove an old one or allowing the tape 2 to travel through its course continuously without being contacted by the contact fingers 77.

As and when the contact 77 are not contacting the tape, no current will flow to the switching mechanism to which the cable wires 80 are connected from the timing mechanism in any instance wherein a radio station is switched in as hereinbefore described.

By referring to Figure 2, the tape 2 at the top of the figure and underneath the fingers 77 is drawn toward the left by the clock or timing movement and thus the tape 2 will pass downward off from the drum 68. To insure the stripping of the tape 2 from the sprocket wheel 69, there is provided the stripping fingers 90, see Figures 2 and 7, which fingers are fastened to a cross block 91 fixed in the framework of the device in any suitable manner.

Referring now to Figures 8, 9, 10, 11, 12, 14 and 15, they relate to the switching mechanisms hereinbefore mentioned and described as magnetically operated switches. In the aforementioned cable 80 there are six conductor wires insulated from each other in the cable. In the diagram of Figure 2 the wire connection 72b enters a transformer 73 which is in turn connected to the terminal block 74. The terminal block 74 is a part of the magnetic switching block as hereinbefore referred to.

The said magnetic switching block is provided with the supporting base herein shown as a flat bed plate 100 made of any suitable material. Extending upward from the base 100, there are the end supporting walls 101 which may be of metal or any suitable material. At the top portion of these walls and on the inside thereof, there is fixed end cross blocks 102 of insulating material. On the top of these blocks 102 there is mounted a plate 103 of insulating material,

which is the top frame plate of the magnetic switch. This plate 103 is fixed on the tops of the end cross blocks 102. The end cross blocks 102 are connected across on the back by the aforementioned terminal block 74.

Mounted to the lower side of the end cross blocks 102, there is a plate 104 of insulating material. On the underside of the plate 104 there are fixed six solenoids as indicated in Figures 8 and 14. These solenoids are all similar in construction and five of them, indicated by 105, being all of those five at the left of Figures 8 and 14, relate to switching in and out for different radio stations, and the other, indicated by 106 or the sixth one being the solenoid at the right of Figure 8, is used in switching off the current to the radio.

The numbers of these solenoids may be more or less than those five indicated as 105 for tuning in on any given program for which this instrument may be provided for.

These solenoids 105 and 106 are substantially alike in construction and are of a construction of more or less common practice as to the details of the part of the solenoids.

The magnetic coil of all of the six solenoids are indicated in Figure 16 as 107. This coil is enclosed by a protecting shell 108 made of iron, see Figure 9. This shell adds to the magnetic power of the solenoid. The plungers used in these solenoids 105 and 106 may be of any suitable construction for the purpose desired, but I prefer to provide a special plunger indicated in cross section in Figure 15 in which the lower end 109 of the plunger is made of soft iron and is suitably connected at its top by a non-magnetic block 110 which may be made from any suitable non-magnetic material. On the inside of the block 110 I provide a screw threaded stem 111 of non-magnetic metal on the top of which there is provided a cone-shaped cap 112. The stem 111 passes through an insulating plate 113, which is a small rectangular plate shown in perspective in Figure 17. Above the plate 113 there is screwed onto the stem 111 a clamping nut 114 of any suitable non-magnetic material. A plate like 113 with its three contacts is provided for the plunger for each of the five solenoids 105 and plate 134 with its contact strip 137, provided for solenoid 106, plates 113 and 134 are each provided with a projection 115 made of the insulating material as that of the plate itself or other suitable form composed of insulating material.

The electrical contact fingers 77 trail along over the insulating tape 2 which is punched with holes S, T, and the contact fingers 77 ride on the tape 2, the unpunched part of it holds the circuit open at fingers 77. When a hole S, T, passes under one of the fingers 77, by spring action the points of these contact fingers drop down through one of the holes S, T, in the tape 2, and thereby close an electrical circuit which causes one of the five solenoids 105 or solenoid 106 to act. This circuit is shown in Fig. 2 and is as follows, one

terminal of all six of the solenoids 105, 106 are connected together to line 121 which is connected to one side of transformer 73. The other side of transformer 73 is connected through line 72b to contact plate 71b and through switch blade 72a to contact plate 71a. The other side of coil 106 terminates in a finger 77 above contact plate 71b, while the remaining five solenoids 105 terminate in contact fingers 77 above contact plate 71a. When those contact fingers 77 are lifted by the tape there is opportunity for a spark or heating

contact which might damage the tape as the circuit is broken. This is overcome by the present invention as each solenoid is mechanically locked up in actuated position and its operating circuit is opened instantly through contact fingers 119, 5 being separated by projection 115 on the plate 113 or 134 on the plunger of the actuated solenoid.

Mounted on the inside underneath the plate 103 there is mounted an interlocking bar 116 having 10 trunnion pins 117 which are hinged into the cross blocks 102. On the lower edge of the interlocking bar 116 there is a curved catch lip 118. The trunnion pins of the bar 116 are located substantially in a direct line above the cone-shaped cap 112 in vertical center line of the solenoids 105 and 106. The lip 118 being offset from the body of the bar 116 causes the gravity action to cause the bar to rock downwardly as the apparatus is normally mounted with the solenoids located in plumb line vertical alignment, the action of gravity on the bar 116 is to cause its hooked shaped catch to swing across the top of the cone cap 112 as and when the cap 112 is below the bar 116 in any given instance of the six solenoids herein indicated.

As and when any solenoid is in its maximum downward position with its cap 112 below the bar 116, gravity tends to cause the catch 118 to swing across over the center of the said cap 112.

On any given impulse upwardly of the solenoid plunger excited by an electrical current, the cap 112 of the plunger contacts the bottom edge of the catch 118 and thereby forces the bar 116 aside until catch 118 is released to swing by gravity to hook under the cap 112 as shown in Figures 8, 9 and 10, thereby locking the solenoid plunger upwardly as shown in Figures 9, 10 and at the left of Figure 8. Thus there becomes broken the electrical circuit which was energized by a contact finger passing through a punched hole in the tape as brought about by timing mechanisms as herein before described. Thus there is prevented by this means any heating current which is brought into service by the switching means of the timing means.

As and when any solenoid is actuated by the electrical current throwing up its plunger to the limit of upward stroke, there is thereby cut off the current which energized the said solenoid. The means of cutting off this current is provided by the block 113 which is mounted on its solenoid plunger and carries the projection 115 which is located between the spring contacts, see Figure 16, which are fastened on the insulating plate 104. These contacts 119 on one side are connected by a conductor wire 120 connected to the electrical coil of the solenoid and the other leg is connected to the conductor wire 121, which is common to all the solenoids as being the return circuit for the six different contact fingers of the timing means controlled by the moving tape herein described.

The sudden upward impulse of each solenoid plunger causes the projection 115 of its insulating block 113 or 134 on the complete upward stroke of the plunger to spread apart its spring contact finger 119 to break the circuit of that solenoid as will be apparent from Figures 9, 10, 13 and 16.

Across the blocks 113 of insulating material there is mounted three strips of electrical conductor material 122 on the blocks 113 for all of the five solenoids 105. The plate like 113 for solenoid 106 is shown at 134 in Fig. 14. Plate 134 controls the power supply circuit 130, 131 which is closed by contact strip 137 when plate 134 is in 75

its lower position shown in Fig. 8 where solenoid 106 is deenergized. The power supply circuit 130, 131 is broken at strip 137 when solenoid 106 is energized.

Mounted on the top edges of the insulating plate 103, there are spring contact fingers 123, see Figures 8, 9, 10 and 12, in groups above each of the solenoids 105. The spring contacts 119 are present with each of the solenoids 105 and 106 in the form indicated by Figures 9, 10 and 11. These spring contact fingers as shown in Figure 12 are arranged in groups of three on each side of the plate 103. Those on the side 124 of the plate 103 are connected to conductor wire lines three in number indicated by 125, all three of which lead to one side of the tuning circuit of the radio. On the other side 126 of the plate 103 the three conductor lines 127 in each group are connected to one side of condensers 128 which are of suitable value, and the other side of the condensers of each group are connected to wires 129 which lead to the other side of the tuning circuit of the radio. In the example shown in Fig. 12, wherein there are three condensers in each group, it is assumed that the radio has three tuning elements such as tuning coils, one condenser of a group would be connected to one tuning coil, a second condenser of one group to a second tuning coil and the third condenser of a group to a third coil, the values of the three condensers in each group being appropriate to whatever kind of radio circuit is employed, as well understood. Hence, each time one of the plungers is held up to thereby operate a selector switch having the contacts like 123, a particular group of three condensers is connected to the radio so as to tune it for a particular station, other stations being tuned when other plungers operate. If the radio circuit has only two tuned circuits, there need be only two condensers in each group 128.

The conductor wires controlled by the solenoid 106 are indicated by 130 and 131 and these conductor wires 130 and 131 constitute the electric circuit of the power supply for the radio.

In the position indicated by Figure 11, the electric current supply is at all times connected up for operating the switching mechanisms involved by the solenoids 105. As and when the timing mechanism carries the tape through the spring fingers to a punched hole arranged for making the contact to the solenoid 106, a projection 115 of a plate 113 moves up between the spring fingers 119 as indicated in Figures 11 and 13 from the position of Figure 11 to that of Figure 13.

Referring now to Figure 14 the terminal block hereinbefore mentioned as 14 is connected at its end to the cross blocks 102. Conductor wire 133 of Figs. 2 and 14 goes to the cable 80 to the timing mechanism and conductor wire 124 extends therefrom to the other terminal of the solenoids 105 and 106.

What is claimed is:

1. Program selector apparatus for changing the tuning of a radio set in accordance with a tape program record, said apparatus comprising means providing a path for the tape, a plurality of tape controlled switches in said path, a plurality of solenoids and circuits therefor each controlled by one of said switches, a plurality of plungers each operated by one of said solenoids, a switch controlled by each of said plungers and controlling the circuit of its respective solenoid, means for holding said plungers in actuated position, a power supply circuit for the radio set, one of said plungers having a switch closing said

power supply circuit when said one plunger is not operated by its solenoid and opening said power supply circuit when said one plunger is operated by its solenoid, tuning devices and circuits therefor controlled by others of said plungers, and means operated on actuation of the plunger of a selected solenoid to release the plunger of the previously energized solenoid and operate its plunger switch to restore the control of such previously energized solenoid to its respective tape controlled switch.

2. Program selector for changing the tuning of a radio set in accordance with a tape program record, said apparatus comprising means providing a path for the tape, a plurality of tape controlled switches in said path, a plurality of solenoids and circuits therefor each controlled by one of said switches for idle or actuated condition, a plunger for each of said solenoids, a power supply circuit for the radio set, one of said plungers having a switch closing said power supply circuit when said one plunger is idle and opening said power supply circuit when said one plunger is actuated, tuning devices operated by others of said plungers, means responsive to the operation of each plunger to open the said circuit for its solenoid instantly after that solenoid is actuated and close that circuit when such solenoid is idle and its plunger is released, and a mechanical latch device constructed and arranged to hold an actuated one of said plungers in actuated position and release the previously actuated one of said plungers.

3. Program selector apparatus for changing the tuning of a radio set in accordance with a tape program record, said apparatus comprising means providing a path for the tape, a plurality of tape controlled switches in said path, a plurality of solenoids and circuits therefor each controlled by one of said switches, a plunger for each of said solenoids, a power supply circuit for the radio set, one of said plungers having a switch closing said power supply circuit when said one plunger is idle and opening said power supply circuit when said one plunger is actuated, tuning devices operated by others of said plungers, means responsive to the operation of each plunger to open the said circuit for its solenoid instantly after that solenoid is rendered active by its tape switch and close that circuit when the plunger of such solenoid is released by its tape switch, a mechanical latch device constructed and arranged to hold the actuated plunger in actuated position and release the previously actuated plunger, and means responsive to the absence of tape in said path to prevent said tape controlled switches from actuating their respective tuning control plungers.

4. Program selector apparatus comprising a series of tape controlled switches, a corresponding series of radio circuit selector switches each having and actuated by a solenoid in circuit with one of said tape switches, a plurality of switches each in series with the circuit of one of said solenoids, means responsive instantly after the actuation of each of said selector switches to open the series switch for its solenoid, and a mechanical latch device common to said selector switches for catching and holding an actuated selector switch in actuated position and for releasing the previously actuated selector switch to the control of its tape switch.

5. Program selector apparatus comprising a tape controlled switch, a selector switch con-

trolled thereby, tuning means controlled by said selector switch, a second tape controlled switch, a selector switch controlled by said second tape switch, a power supply circuit controlled by said second selector switch, a latch for holding either of said selector switches in operated position and releasing the other, each of said selector switches having means for operating said latch also having means for removing itself from control of its tape switch when held by said latch, said first selector switch being in closed position when held by said latch, and said second selector switch being in closed position when released from said latch.

15 6. Program selector apparatus for changing the tuning of a radio set in accordance with a tape program record, said apparatus comprising means providing a path for the tape, a plurality of tape controlled switches in said path, a selector switch and associated solenoid for and controlled by each of said tape switches, a tuning device controlled by each of said selector switches, and tape operated means responsive to the absence of tape in said path to remove said solenoids from control of said tape switches and prevent said tape controlled switches from actuating their respective selector switches.

30 7. Program selector apparatus comprising a series of station switches, timed controlled means for selectively rendering said switches operative, a corresponding series of solenoids controlled by said switches, each of said solenoids having a plunger, a series of tuning switches one for each of said plungers, each of said plungers actuating its tuning switch when that plunger is actuated, a corresponding series of breaker switches each in series with its respective solenoid, each of said plungers having means for opening its respective breaker switch when the plunger is actuated, a series of tuning elements, one for each of said tuning switches, and a latch bar common to said plungers, said latch bar having catch and release means operative to catch any one of said plungers when it is actuated and release any 45 previously actuated one of said plungers, each of said breaker switches being closed when its respective plunger is in idle position released from said latch bar.
